US0D1035274S

(12) **United States Design Patent** (10) **Patent No.:** **US D1,035,274 S**
(45) **Date of Patent:** **** Jul. 16, 2024**

(54) **STORAGE CHEST**

(71) Applicant: **APEX BRANDS, INC.**, Apex, NC (US)

(72) Inventors: **Richard A. Samsel**, Haines City, FL (US); **Jonathan Ezequiel-Shriro**, St. Louis, MO (US); **Matthew Poppe**, Holly Springs, NC (US); **Jason Mars**, Jonesboro, AR (US); **Michael Taber**, Jonesboro, AR (US)

(73) Assignee: **APEX BRANDS, INC.**, Apex, NC (US)

(**) Term: **15 Years**

(21) Appl. No.: **29/776,307**

(22) Filed: **Mar. 29, 2021**

Related U.S. Application Data

(60) Continuation of application No. 29/772,867, filed on Mar. 4, 2021, which is a division of application No. 29/661,155, filed on Aug. 24, 2018, now Pat. No. Des. 914,365, application No. 29/776,307 is a continuation of application No. 29/661,155, filed on Aug. 24, 2018, now Pat. No. Des. 914,365.

CLAIM

The ornamental design for a storage chest, as shown and described.

DESCRIPTION

FIG. 1 is a perspective front view of a storage chest where the lid of the storage chest is in an open position in accordance with the present design; and,

FIG. 2 is a front view of the storage chest of FIG. 1.

Any broken lines of the storage chest in FIGS. 1-2 are illustrative of portions of the storage chest that form no part of the claimed design.

1 Claim, 2 Drawing Sheets

FIG. 1

FIG. 2
